UNITED STATES PATENT OFFICE.

ARTHUR L. PAYTON, OF CHICAGO, ILLINOIS.

CARBURETER.

1,241,547.

Specification of Letters Patent.

Patented Oct. 2, 1917.

Application filed January 19, 1916. Serial No. 72,945.

To all whom it may concern:

Be it known that I, ARTHUR L. PAYTON, a citizen of the United States, residing at Chicago, in the county of Cook and State of Illinois, have invented a certain new and useful Improvement in Carbureters, of which the following is a full, clear, concise, and exact description, reference being had to the accompanying drawings, forming a part of this specification.

My invention relates to carbureters for internal combustion engines and has for its object the provision of simple and effective means for supplying fuel to the fuel or float chamber of the carbureter from a fuel reservoir located at a point below the float chamber of the carbureter.

The object of my invention is to utilize the suction or vacuum created in the atomizing chamber of the carbureter for providing and maintaining a difference of pressure between the supply reservoir and the float chamber. The float chamber of the carbureter is arranged to communicate by means of a conduit with the fuel reservoir. The fuel reservoir is provided with a vent so that the fuel contained therein is subjected to atmospheric pressure, which, when the float chamber contains a pressure which is less than the atmosphere, serves to transport the fuel from the fuel reservoir to the float chamber of the carbureter. A suitable valve mechanism is employed within the float chamber so that the transportation of fuel from the supply reservoir to the carbureter does not take place unless the level of the fuel within the float chamber falls below a predetermined height.

To provide the vacuum or reduction of pressure within the float chamber of the carbureter I provide an opening communicating with the float chamber at a point above the fuel level and atomizing chamber of the carbureter, or any other portion of the carbureter in which a vacuum or reduction of pressure is produced during the operation of the internal combustion engine with which the carbureter is associated.

My invention consists in the arrangement and combination of parts and instrumentalities, set forth in the following detail description and claimed in the appended claims.

My invention will be more clearly understood by referring to the accompanying

drawing which illustrates diagrammatically a carbureter and a fuel reservoir located at a point below the normal fuel level within the fuel chamber of the carbureter.

The carbureter is illustrated at 1, provided with the usual flanges 2 to facilitate connection between the carbureter and the intake manifold of the internal combustion engine. The carbureter contains the usual atomizing chamber 5 into which extends the fuel nozzle 6 terminating at its lower end in the fuel or float chamber 7. The nozzle 6 may, if desired, extend through the float 8 to form a guide therefor, and may have a manually operated valve 9 for controlling the fuel passageway therein. Pivoted at 10 is a lever 11, resting upon the upper face of the float 8. This lever is provided with a valve member 12 arranged to open and close when the float is moved up and down, an opening 13 communicating with the conduit 14. The conduit 14 extends downwardly into the supply reservoir 15, the lower end of the conduit being positioned adjacent the bottom of the reservoir. 16 illustrates a vent provided in the reservoir and serves to permit the fuel contained therein to be subjected to atmospheric pressure.

17 illustrates the throttle valve which is under the control of the operator and serves to enable the operator to control the supply of fuel to the internal combustion engine.

Located in the intake port 18 of the carbureter is a valve 19 normally held against its seat 20 by means of a compression spring 21. This spring 21 is interposed between the valve 19 and a spider 22 supported from the casing. The float chamber 7 has communication with the intake port through an opening 23. A second valve is provided at 24, which is disposed between the opening 23 and that portion of the atomizing chamber into which the nozzle 6 extends. This valve is normally held against its seat 25 by means of a compression spring 26 extending between the valve and a spider 27 carried by the casing. The compression spring 26 serves the function of providing a difference in pressure between that portion of the atomizing chamber 5 which is immediately adjacent the nozzle 6 and the interior of the float chamber 7. The spring 21 which is provided on the outside of the opening 23 is arranged to control or determine the amount

of pressure reduction which is obtained within the float chamber, due to the suction created by the engine.

The operation of the device just described is as follows:

As the internal combustion engine is operated a vacuum or partial vacuum is produced in the atomizing chamber 5, and after a certain predetermined reduction of pressure is produced in this chamber, the valve 24 will be opened against the tension of the spring 26. The opening of this valve will subject the chamber 28 to the suction produced by the internal combustion engine, the result being the extraction of air from the fuel chamber 7 through the opening 23. After a certain predetermined reduction of pressure is produced within the chamber 28, the valve 19 is arranged to open to permit the intake of air into the carburetor. The spring 21 and valve 19 therefore determine the degree of reduction of pressure, which is produced within the fuel chamber 7, and the valve 24 and spring 26 determine the degree of difference between the pressures of the atomizing chamber 5 and the fuel chamber 7. I have found that a one pound pressure reduction in the chamber 28 is sufficient to raise the fuel for a distance of about thirty inches, which is sufficient for most purposes where the carburetor is used in connection with automobiles. When, therefore, it is desired to operate the system on a one pound pressure reduction, the valve 19 is arranged so that it will open the intake port of the carburetor when a one pound pressure reduction is obtained within the chamber 28.

When during the operation of the carburetor the fuel level within the float chamber 7 is lowered, the float 8 is accordingly lowered to open the valve 12. The conduit 14 then has a free communication between the supply reservoir 15 and the interior of the fuel chamber. As soon, therefore, as the valve 12 is opened, the difference in pressure between the supply reservoir and the fuel chamber will cause the gasoline to be forced upwardly through the conduit 14 into the fuel chamber. When the level within the fuel chamber has again reached its normal height, the float will close the valve 12 and discontinue the flow of fuel through the conduit 14 until the fuel level has again receded. Due to the fact that the conduit 14 empties into the float chamber at a point above the fuel level therein, at no time, regardless of the position of the valve 12, can the supply of fuel in the float chamber return to the reservoir.

Having thus described my invention, what I claim as new and desire to secure by Letters Patent of the United States, is:

1. A carburetor provided with a passageway therethrough terminating in intake and outlet ports, and a fuel chamber, a fuel nozzle

affording communication between the fuel chamber and the passageway, an automatic valve seating against atmospheric pressure disposed in the passageway between the fuel nozzle and the intake port for restricting the passage of air through the carburetor, the valve being arranged, when closed, to entirely prevent the passage of air through the passageway, and a second automatic valve normally seated against atmospheric pressure disposed in the passageway between the first mentioned valve and intake port for restricting the passage of air through the carburetor, said valves serving to maintain a substantially constant pressure reduction for the space between them, the portion of the fuel chamber above the normal fuel level therein communicating with the passageway at a point between the two valves.

2. A carburetor provided with a passageway therethrough terminating in intake and outlet ports, and a fuel chamber, a fuel nozzle affording communication between the fuel chamber and the passageway, an automatic valve seating against atmospheric pressure disposed in the passageway between the fuel nozzle and intake port for restricting the passage of air through the carburetor, the valve being arranged, when closed, to entirely prevent the passage of air through the passageway, a second automatic valve, normally seating against atmospheric pressure disposed in the passageway between the first mentioned valve and the intake port for restricting the passage of air through the carburetor, said valves serving to maintain a substantially constant pressure reduction for the space between them, the portion of the fuel chamber above the normal fuel level therein communicating with the passageway at a point between the two valves, a supply reservoir, a conduit connecting the reservoir with the fuel chamber, a valve for controlling the transportation of fuel through the conduit and a float in the fuel chamber for operating the valve.

3. A suction feed carburetor provided with a single air intake, a pair of automatic valves serially situated in the air intake anterior to the atomizing chamber of the carburetor, and a throttle posterior to said atomizing chamber, a supply reservoir adjacent the atomizing chamber, a spray nozzle in the atomizing chamber and conductively connected with the gasoline of the reservoir, the upper spaces of the reservoir above the gasoline therein being conductively connected with the space between said serially arranged automatic valves, whereby the suction producing means for the carburetor will maintain a pressure in the reservoir, which is a differential between the atmospheric pressure and that within the atomizing chamber of the carburetor.

4. A carburetor provided with an atomiz-

ing chamber and a float chamber, a main source of supply below the level of the float chamber, a pair of serially arranged automatic valves through which all of the air
5 admitted to said atomizing chamber passes, a manually operated throttle posterior to said atomizing chamber, a duct connecting the spaces between said automatic valves with the upper part of the float chamber, a
10 spray nozzle in the atomizing chamber and a duct connecting said spray nozzle with the lower part of said float chamber.

5. A carbureter of the suction type provided with an atomizing chamber, a throttle
15 posterior to said chamber and a pair of serially arranged automatic valves anterior to said atomizing chamber, a float chamber, a main source of fuel supply, a conduit extending from said main source of fuel supply
20 and communicating with the upper part of said float chamber, a valve for closing the opening between said conduit and float chamber, a float in the float chamber controlling said valve, a spray nozzle in the
25 atomizing chamber conductively communicating with the lower part of the float chamber and conduit connecting the upper parts of the float chamber with the space between said automatic valves.
30 6. A carbureter for suction feed internal

combustion engines provided with an atomizing chamber, a pair of serially arranged automatic valves anterior to said atomizing chamber and serving as a restriction to the main supply of air to said atomizing chamber, a float chamber having its upper spaces conductively connected with the space between said automatic valves, a main supply tank and a conduit connecting the lower part of said main supply tank with the upper part of said float chamber, a float in the float chamber and a valve controlled by said float for opening and closing the port between the main supply source and said float chamber, the opening from said supply conduit into the float chamber being above the level of the gasolene in the float chamber, so that gasolene cannot return from the float chamber to the main source of supply, the combination being such that gasolene will be forced into the float chamber by atmospheric pressure upon the surface of the gasolene of the main supply source.

In witness whereof, I hereunto subscribe my name this 17th day of January, A. D. 55
1916.

ARTHUR L. PAYTON.
